WIRE TWISTING APPARATUS

Filed Sept. 5, 1928

Inventor

R.B.Brannaka

By Watson E. Coleman
Attorney

UNITED STATES PATENT OFFICE

ROBERT B. BRANNAKA, OF ROARING BRANCH, PENNSYLVANIA

WIRE-TWISTING APPARATUS

Application filed September 5, 1928. Serial No. 304,061.

This invention relates to a wire twisting apparatus and it is primarily an object of the invention to provide a device of this kind adapted for use in the production of tie wires for electric lines or the like and particularly that type of tie wire wherein each or both ends thereof are provided with eye members or loops to facilitate the removal of the tie wire.

10 Another object of the invention is to provide an apparatus of this kind of a portable type which can be readily transported by an individual from one locality to another as the occasions of practice may necessitate.

15 Furthermore, it is an object of the invention to provide a device of this kind comprising a supporting or base member rotatably carrying a shaft having an outstanding eye forming member with which the wire to be 20 twisted is engaged, the rotation of the shaft resulting in the requisite twisting of the wire to produce the desired eye member.

The invention consists in the details of construction and in the combination and arrangement of the several parts of my improved wire twisting apparatus whereby certain important advantages are attained and the device rendered simpler, less expensive and otherwise more convenient and advantageous for 30 use, as will be hereinafter more fully set forth.

The novel features of my invention will hereinafter be definitely claimed.

In order that my invention may be the better understood, I will now proceed to describe 35 the same with reference to the accompanying drawing, wherein:—

Figure 1 is a view in top plan of a wire twisting apparatus constructed in accordance with an embodiment of my invention, an associated wire strand being diagrammatically indicated by broken lines;

Figure 2 is a sectional view taken substantially on the line 2—2 of Figure 1, the wire strand being also indicated by broken lines;

40 Figure 3 is a detailed sectional view taken substantially on the line 3—3 of Figure 1;

Figure 4 is a fragmentary view in detail partly in section and partly in elevation illustrating the mounting of the eye forming member with respect to the shaft;

Figure 5 is a view in perspective illustrating the formation of the wire with respect to the apparatus before the twisting action;

Figure 6 is a fragmentary view of an end portion of the wire after twisting action.

As disclosed in the accompanying drawing, B denotes a base or supporting member of requisite dimensions and of any preferred material and which at approximately its central portion is provided therethrough with a slot 1 of required dimensions. This slot 1 has in communication therewith an opening 2 disposed substantially at right angles thereto, said opening being directed through the base or supporting member B to one side of the slot 1 and opening at a side of said member B.

Insertible from without through the opening 2 is an elongated shaft 3, said shaft being of a length to have its inner end portion extend within the slot 1, as particularly illustrated in Figure 1, while the outer or opposite end of the shaft 3 is formed to provide an operating crank 4. It is to be understood, however, that if desired any means other than a crank 4 may be employed to effect the requisite rotation to the shaft 3.

The inner or inserted end portion of the shaft 3, as herein disclosed, is flattened, as at 5, to provide a seat for the larger or base end of an elongated tapered pin 6. This larger or base end of the pin 6 carries a threaded extension 7 for requisite engagement with the inserted end portion of the shaft 3 whereby said pin 6 is effectively held in applied or working position yet can be readily and conveniently removed when it is desired to replace the pin 6 and particularly when it is desired to use a pin of a different size.

While in the accompanying drawing I only disclose a single pin 6 it is to be noted that in practice as many of such pins will be provided as required in the working operation, the size of each of such pins 6 determining the mean or inner diameter of the eye member to be formed at the extremity of a tie wire.

The pin 6 is in perpendicular relation to the shaft 3 when applied and it is to be noted that the slot 1 is of a length to permit the shaft 3 to be rotated without any hindrance or

obstruction to such rotation being offered by the pin 6.

The upper surface of the base or supporting member B at the side thereof remote from the shaft 3 is provided with a groove or channel 8 the same bridging the space between the slot 1 and the side of the member B. This groove or channel 8 is of a depth to receive an end portion of a tie wire T to be worked and said portion of the wire within the groove or channel 8 is held against displacement therefrom, and more especially during a working operation, through the instrumentality of a plate 10 slidably supported upon the upper surface of the base or supporting member B. This plate 10 when in applied position, as indicated by full lines in Figure 1, overlies the groove or channel 8 and thereby effectively holds the applied wire strand T against displacement. When moved in the opposite direction, as indicated by broken lines in Figure 1, the plate 10 will be free of the groove or channel 8, thus permitting unhampered application or removal of the tie wire or strand T.

While the plate 10 may be supported upon the base or supporting member B in any desired manner, in the present embodiment of my invention said plate is provided with a longitudinally disposed slot 11 through which is freely directed a headed retaining member 12 carried by the base member B and said plate 10 is also provided at one end portion, and preferably at that end remote from the slot 11, with an upstanding operating knob or finger piece 14.

The upper surface of the base or supporting member B in close proximity to the junction of the groove or channel 8 with the slot 1 is provided with an opening or recess 15.

When it is desired to form an end portion of a wire strand, such as a tie wire used by linemen, an end portion of the wire or strand is inserted within the opening or recess 15 whereupon the workman initially bends the wire around the pin 6 and then positions the outer portion of the wire within the groove or channel 8 in a manner as is believed to be clearly indicated in Figures 1 and 2 of the drawing, the resultant initial bending of the tie wire or strand by the operator being also illustrated in Figure 5. By inserting an end portion of the wire or strand within the opening or recess 15, said end portion of the strand is effectively held during the period the wire is being bent around the pin 6 and being initially placed within the groove or channel 8. This initial anchoring of the end portion of the wire or strand also facilitates the desired twisting of the wire or strand. With the tie wire or strand applied as just described the operator imparts requisite rotation to the shaft 3 as through the medium of the crank 4, resulting in the portions of the strand or wire T in advance of the pin 6 being

twisted one around the other and thus upon a few rotations of the shaft 3 producing a desired eye member at an end portion of the wire strand, the size of said eye member, and more particularly its inner or mean diameter, being determined by the diameter of the pin 6 adjacent to its base.

An apparatus of this kind is particularly advantageous for use by those persons engaged in hot line maintenance as work of this kind is of an extremely dangerous character and operations in connection therewith must be performed with great care. It is for this reason that it is now becoming the practice to provide the tie wires for holding a conductor line to an insulator, such as of a high tension type, with eye members, said eye members providing means whereby a hook carried by a hot stick may be readily engaged within an eye member to permit the tie wire being readily released from its applied or working position.

From the foregoing description it is thought to be obvious that a wire twisting apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A wire twisting apparatus comprising a member, a shaft rotatably supported by the member and provided with an eye forming finger, said member being provided with a recess to receive an end portion of the wire to be twisted before said wire is initially engaged around the finger.

2. A wire twisting apparatus comprising a member, a shaft rotatably supported by the member and provided with an eye forming finger, said member being provided with a recess to receive an end portion of the wire to be twisted before said wire is initially engaged around the finger, and means for holding the opposite end portion of the wire to the member.

3. A wire twisting apparatus comprising a member, a shaft rotatably supported by the member and provided with an eye forming finger, said member being provided with a recess to receive an end portion of the wire to be twisted before said wire is initially engaged around the finger, and means for holding the opposite end portion of the wire to the member, said means including a channel to receive said portion of the wire, and a part

adapted to extend across the groove to hold the wire against displacement therefrom.

4. An apparatus of the class described comprising a base member having an elongated slot disposed therethrough, a shaft rotatably supported by said member and having an end portion extending beyond a side wall of the slot, an eye forming finger carried by said extended portion of the shaft, said base member adjacent to the slot and at the side thereof remote from the shaft being provided with a recess to receive an end portion of a wire strand before said strand is initially disposed around the eye forming finger.

15 In testimony whereof I hereunto affix my signature.

ROBERT B. BRANNAKA.
